UNITED STATES PATENT OFFICE.

GOTTLIEB G. DUFLOTH, OF TOLSTOY, SOUTH DAKOTA.

TANK-GAGE.

1,106,552.

Specification of Letters Patent. Patented Aug. 11, 1914.

Application filed November 2, 1911. Serial No. 658,180.

To all whom it may concern:

Be it known that I, GOTTLIEB G. DUFLOTH, a citizen of the United States, residing at Tolstoy, in the county of Potter and State 5 of South Dakota, have invented certain new and useful Improvements in Tank-Gages, of which the following is a specification.

This invention relates to an improvement in gages especially adapted for use in connection with motor vehicles for readily ascertaining the amount of gasoline in the tank.

The principal object of this invention is to provide a gage for the purpose specified 15 which can be readily attached to or removed from the dash-board of a vehicle.

Another object of the invention is to provide a gage of the character described, which consists of a glass tube having caps 20 secured to the ends thereof in a novel manner, and attaching means for the gage carried by the caps.

A further object of the invention is to provide a gage of a minimum number of 25 parts, which is therefore simple in construction, and is cheap to manufacture.

With these and other objects in view, the invention consists in the construction and novel combination of parts hereinafter fully 30 described, illustrated in the accompanying drawings, and pointed out in the claim hereunto appended; it being understood that various changes in the form, proportion, size and minor details of construction within the 35 scope of the claim may be resorted to without departing from the spirit or sacrificing any of the advantages of the invention.

In the drawing: Figure 1 is a detail side elevation of a motor vehicle equipped with 40 a gage constructed in accordance with my invention. Fig. 2 is an enlarged side elevation of the gage. Fig. 3 is a longitudinal section therethrough. Fig. 4 is a top plan view.

45 Like reference numerals designate corresponding parts in all the figures of the drawing.

Referring to the drawing, 5 designates a motor vehicle including the usual dash- 50 board. Supported by the body is the usual gasoline supply tank 7 having a spigot 8.

55 My invention comprises a gage by means of which the amount of gasoline within the tank 7 may be readily observed. This gage consists of an open-ended glass tube 9, and upper and lower caps 10-11 respectively

connected to the ends thereof. The upper cap 10 is formed from a single casting which is formed at its lower end with a recess 12 for snugly receiving the upper end 60 of the tube. The exterior face of the lower end of the cap is threaded, as indicated by the numeral 13 for engagement with a nut 14 having at its base an inwardly extending flange 15 by means of which a gasket 16 65 may be compressed laterally against the tube, and thereby create an air-tight connection. The body of the cap is formed with a central opening 10^a which communicates with the recess 12 and the atmosphere. The lower cap is also formed from a solid casting, and this casting is formed with a bore 17 and counterbore 18, which forms a resultant shoulder 19 upon which the lower edge of the tube is seated. The outer face 70 of the upper portion of the cap is threaded, as indicated by the numeral 20, for engagement with a nut 21 having at its top an inwardly extending flange 22 by means of which a gasket 23 may be readily compressed laterally against the tube to create an air-tight connection. A spigot 24 extends laterally from the cap 11 and a port 25 communicates with the spigot and bore 17. 75

Integral with each cap is a plurality of laterally extending arms 26, each arm being formed with an opening 27. Disposed within the openings 27 of each pair of arms is a rod 28, one end being formed with a head 29 and the other end having a nut 30 associated therewith. These rods not only act as guards to prevent the tube from becoming accidentally broken, but also constitute means for securing the caps to the tube. 90 These rods are each further provided with a scale, which is indicated by the numeral 31, by means of which the amount of gasoline within the tank can be definitely ascertained. 95

In order to attach the gage to the dash-board 6, each cap is provided with a pair of laterally extending arms 37-37, each pair being disposed between a pair of rods 28 and projecting forwardly beyond the same. Each pair of these arms is adapted to straddle one edge of the dash-board, and is secured thereto by rivets or other suitable fastening means.

A pipe 33 is connected at one end to the 110 spigot 8 of the tank 7 and at its other end to the spigot 24 of the lower cap 11, thereby

permitting the gasoline to pass from the tank to the gage.

What is claimed is:

- The combination with a glass tube, of 5 caps for the upper and lower ends thereof, the upper cap having a longitudinal opening communicating with the tube and with the atmosphere, the lower cap having a bore therein and a counter bore communicating 10 with the bore, said cap also having a port leading to the counterbore, a pipe attaching member communicating with the port of the cap, laterally extending spaced arms projecting from the caps, rods extending be-

tween the arms and parallel to the tube, 15 and means for independently adjusting the effective lengths of said rods, and spaced parallel arms projecting from the caps between the rods and adapted to straddle the edge of a vehicle dash-board to attach the 20 gage thereto.

In testimony whereof I affix my signature, in the presence of two witnesses.

GOTTLIEB G. DUFLOTH.
